UNITED STATES PATENT OFFICE

2,068,602

HAIR CURLER

Abraham Goodman, Brooklyn, N. Y., assignor to
 Delamere Company, Inc., a corporation of Delaware

Application August 15, 1933, Serial No. 685,172

3 Claims. (Cl. 132—41)

The present invention relates to hair-curling devices of the general type in which there is a form, commonly a hollow tube, around which the hair is wound, and an arm or other member 5 for holding the hair in place on the tube; and relates to a more specific type in which the hair-retaining member is elastic, to be stretched over the hair, from a fixed connection at one end of the tube, to some means at the other end of the tube for holding the elastic in stretched, hair-retaining position. More particularly, the invention relates to improved means whereby to lock the elastic in hair-retaining position, and to release the same therefrom.

Heretofore, in devices of this latter character, some exploration with the fingers, fumbling and pulling of the hair has commonly been involved in finding the proper point of the elastic member to be seized for stretching thereof to locking 15 position, and more especially for unlocking the same. Other devices have presented difficulties in finding and bringing together the co-acting locking elements on the elastic member and tube; and in disconnecting or unlocking these members without pulling of the hair; while in still others of the devices the lock has been uncertain in its hold, or becomes so by wearing of the locking elements. Again, in other devices finger-pieces for manipulating the hair-retaining 20 element, and the locking elements themselves, have been of shape, size or material such as to be uncomfortable to the wearer, or unnecessarily unsightly.

An object of the invention is the provision of a 25 finger piece, in the form of a loop in the elastic member itself, whereby the elastic member may with certainty be seized at the proper point thereof for stretching the same to locking position, and for unlocking the same. A further object 30 of the invention is the provision of a locking element so mounted and fixed upon the elastic hair-retaining member, behind the finger piece or loop thereof, that when the elastic member is tensioned by the finger piece, the locking element is under a comparatively rigid control, and is not free to hang or wobble, or to require the 35 same to be seized or guided by the operator's fingers.

The foregoing and other objects and features 40 of the invention will appear more fully from the following description thereof, it being understood that modifications in the details herein described and shown may be made without departing from the spirit and scope of the invention.

The invention is illustrated in the accompanying drawing, in which:

Figure 1 is a top plan view of the device in locked condition;

Fig. 2 is a sectional view taken on the line 2—2 of Fig. 1;

Fig. 3 is a view in perspective of the device in unlocked condition;

Fig. 4 shows a sheet metal blank out of which a combined hook and clinch for the finger-piece 10 loop on the cord may be formed; and,

Fig. 5 is a top plan view of a modified form of the device with the elastic retaining cord in unlocked position.

Referring to Figs. 1 and 2, the device is shown 15 as comprising a hollow tube 10, of familiar style, made of light sheet metal, perforated as at 11 for hair-drying circulation of air, and open at both ends 12 and 13.

Secured to the end 12 of tube 10, as by being 20 passed through one of the perforations 11 and then knotted at 14 at one end, in such manner that the knot is within the tube and will not pass through the perforation, is an elastic cord 15. This cord, so anchored at one end to one end 25 of the tube, has its other, or free, or distal end made into a loop 16, which serves as the finger-piece hereinbefore mentioned.

This finger-piece loop in the cord is made by 30 turning the distal end of the cord back on itself, and by clinching the end of the cord to the side of the cord, as by a sheet metal band 17. In the preferred form of the invention this band 35 17 is formed from a part 18 of the blank 19, shown in Fig. 4, from which the hook, hereinbefore mentioned, is also preferably made.

The hook 20 is shown in the drawing as mounted 40 on the cord 15 at the base of the loop 16, so that the fingers grasp the cord beyond the hook in drawing the hook to locking position, and in releasing the hook. There is therefore no gravity droop of the hook as it comes into or out of locking position; it is at all such times under fairly rigid control; and the locking and unlocking movements may therefore always be quick 45 and sure. Preferably, as shown in Fig. 4, the hook is stamped from a sheet metal blank 19, having a part 18, as above stated, from which the finger-piece clinch is formed.

In operation, the hair is wound in the usual 50 manner upon the hollow tubular form 10; the cord 15 being thrown to one side so that free swing of the hand and hair may be had without any manipulating of the hair under the cord. 55

The cord is then seized by the finger piece 16, and drawn lengthwise of the tube, and down upon the hair, until by stretching the elastic, the hook 20 passes the end 13 of the tube, whereupon the 5 hook is pressed behind said end and snaps into interlocking engagement with the rim or edge thereof, to be held so locked against all accidental displacement by the tension of the cord itself. To unlock the device, it is merely necessary to 10 take hold of the finger-piece 16 and pull on the same, to stretch the cord sufficiently to pass the hook clear of the tube end 13.

In the modification shown in Fig. 5, a free end portion 21 of the loop or finger-piece 16 extends 15 beyond the band 17 and carries a ball 22 at its extremity, which ball is preferably of smaller diameter than the open end 13 of the tube 10. Said open end forms a socket for receiving the ball, and is provided at its edge with a slot 23 20 that engages the end portion 21 of the elastic hair-retaining cord 15, when the latter is in locked position, to hold the ball in place by the tension of the cord and to securely lock the parts.

What I claim is:—

25 1. A hair curler comprising a tubular member around which hair may be wound, an elastic clamping member secured to one end of the tubular member and stretchable lengthwise of the tubular member over the hair wound thereon, 30 fastening means at the free end of the clamping member for detachably fastening said end to

the opposite end of the tubular member, and a finger grip piece carried at the free end of the clamping member and extending outwardly beyond the fastening means.

2. A hair curler comprising a tubular member 5 around which hair may be wound, an elastic clamping cord secured to one end of the tubular member and stretchable lengthwise of the tubular member over the hair wound thereon, the free end of said clamping cord being formed into a 10 loop to provide a finger grip piece, a clinching band securing the ends of the loop, and a hook on the clinching band for detachably fastening the free end of the elastic clamping cord to the opposite end of the tubular member, said finger 15 grip piece extending outwardly beyond the hook.

3. A hair curler comprising an open-ended tubular member around which hair may be wound, an elastic clamping cord secured to one end of the tubular member and stretchable 20 lengthwise of the tubular member over the hair wound thereon, the free end of said clamping cord being turned back on itself and clinched to form a finger grip loop, a ball carried at the extremity of the clamping cord and adapted to be 25 removably inserted into the opposite open end of the tubular member for detachably fastening the free end of the clamping cord to said end of the tubular member, said finger grip loop extending outwardly beyond the ball.

30 ABRAHAM GOODMAN.
